FIRE EXTINGUISHING SYSTEM

Delbert G. Faust, Caldwell, N. J., assignor to Specialties Development Corporation, Belleville, N. J., a corporation of New Jersey

Application January 8, 1949, Serial No. 69,972

3 Claims. (Cl. 169—2)

1

The present invention relates to fire extinguishing systems and more particularly to such systems utilizing a plurality of cartridges containing a fire extinguishing agent adapted to be directed to a fire hazard in a compartment by remotely controlled pressure providing means.

An object of the present invention is to provide a fire extinguishing system which is simple in construction, effective in operation, and is readily adaptable for selectively protecting one or more fire hazards located in the same or different compartments or spaces.

Another object is to provide a system which is light in weight, occupies a minimum amount of space, and is particularly adapted for use on airplanes, power boats and like installations, where weight or space are important factors.

Another object is to provide a system wherein cartridges containing the fire extinguishing agent are located adjacent the hazards to be protected, thus simplifying the problem of distributing the agent.

A further object is to provide a system wherein the fire extinguishing agent is stored in readily chargeable removably mounted cartridges, thus simplifying inspection and maintenance of the system.

Other and further objects of the invention will be obvious upon an understanding of the illustrative embodiment about to be described, or will be indicated in the appended claims, and various advantages not referred to herein will occur to one skilled in the art upon employment of the invention in practice.

In accordance with the invention, these objects may be generally accomplished by providing a system comprising one or more readily chargeable fire extinguishing agent containing cartridges in or adjacent the compartment in which there is a fire hazard, means associated with one end of the cartridges arranged for directing the agent towards the hazard, pressure providing means associated with the other end of the cartridges adapted to expel the agent, and means at the exterior of the compartment for controlling the pressure providing means. The cartridges preferably are removably mounted and are in the form of a tubular casing having closures at its ends, including displaceable or rupturable means, such as sealing discs or the like for confining the

2

charge, which have the directing and pressure providing means operatively associated therewith. The cartridges may be discharged by a combustible or explosive powder fired by means actuated at a remote location or may be discharged by a source of fluid pressure medium released by means controlled from a remote location.

In the drawings:

Figure 1 is a schematic view of an airplane fire extinguishing system illustrating an embodiment of the present invention, wherein the system is adapted for electrical operation.

Figure 2 is a longitudinal sectional view of one of the fire extinguishing agent containing cartridges used in connection with the system shown in Figure 1.

Figure 3 is a sectional view taken along the line 3—3 on Figure 2.

Figure 4 is a fragmentary view, partly in section and partly in elevation, of another form of discharge directing means adapted to be connected to the outlet end of the cartridge.

Figure 5 is a schematic view of an airplane fire extinguishing system illustrating another embodiment of the present invention, wherein the system is adapted for fluid pressure medium operation.

Figure 6 is a fragmentary view, partly in elevation and partly in longitudinal section, of the pressure medium inlet end of one of the cartridges used in connection with the system shown in Figure 5.

Referring to the drawings in detail and more particularly to Figure 1 thereof, there is shown a fire extinguishing system applied to a compartment such as a nacelle 10 of an airplane. The nacelle generally has three zones which require independent fire protection against the hazard therein. Usually, these zones comprise a forward zone 11, known as the power section, in which the engine is located; an intermediate zone 12, known as the accessory section, in which the carburetor, oil pump and other engine accessories are located; and a rear zone 14, in which the wheel well, wing defroster or other miscellaneous apparatus to be protected against fire are located. A fire wall 15 preferably separates the intermediate zone from the rear zone. While the system in accordance with the present invention is particularly adapted for airplane

nacelle protection, it is in no way limited to such exploitation, the nacelle being an example of one of the many uses of the system for protecting a compartment or several contiguous zones in a compartment.

The fire extinguishing system comprises one or more fire extinguishing agent containing cartridges 16, described in detail hereinafter, removably mounted in or adjacent each of the zones 11, 12 and 14 and positioned to discharge the fire extinguishing agent in a direction most effective to protect the fire hazard in the respective zones. As illustrated herein, two such cartridges are provided in each zone, by way of example, and these cartridges are of the type wherein a charge of a pressure producing substance, such as gunpowder or the like, is adapted to be ignited by electrically heating a resistance element.

Preferably, ignition of the pressure producing substance is controlled from a remote location such as a central control panel 17, generally indicated by the broken lines, located in the pilot's or engineer's quarters of the airplane. If desired, the cartridges for the respective zones may be operated selectively or simultaneously at the will of the operator, and, to accomplish this, an electrical circuit is provided which comprises a source of electrical energy such as a battery 19, sets of wires 20 connecting the cartridges for each zone in parallel for conducting energy from the source to each of the heating elements, and a switch 21 for each set located on the control panel 17.

It will be understood, without further illustration or detailed description, that the pressure producing substance could be ignited by a percussion cap or the like which could be detonated by a firing pin associated with a solenoid or a spring operated trigger mechanism arranged in and under the control of the electrical circuit. It is also contemplated that the firing pin could be operated remotely by a fluid pressure energized piston, and that the trigger mechanism could be operated remotely by a pull cable, the supply of fluid pressure medium and the operation of the pull cable being controlled from the control panel 17.

In Figure 2, a cartridge 16 is shown which is constructed and arranged to facilitate charging and removable mounting thereof. This cartridge contains a fire extinguishing powder or liquid and comprises a tubular casing 26 having an inlet opening 27 at one end and an outlet opening 29 at the opposite end, and closures 30 and 31 for the respective openings, including rupturable discs 32 for confining the charge in the casing. If desired, the discs 32 may be omitted by pre-packaging the charge in a container shaped for insertion into the casing and having rupturable end walls taking the place of the discs 32.

The closure 30, as shown, may be a cap-like element comprising an upper internally threaded sleeve portion 34 for receiving and attaching the inlet end portion of the casing 26, an inwardly extending shoulder 35 cooperating with the inlet end of the casing to secure the disc 32 therebetween, a central bore 36 for the reception of pressure providing means 37 in fluid flow communication with the inlet opening 27, herein shown by way of example as an electrically ignited powder containing cartridge element, and a lower outwardly extending flange 39 adapted for removable securement to a base member 40 or the like on the structure 41 of the craft by means of a flanged screw collar 42.

The cartridge element 37 has an electrical re-

sistance element therein, such as a bridge wire 44 supported by leg wires 45 connected to connectors 46, and is supported in the upper portion of the bore 36 by a plug 47 of insulating material secured in the bore and having electrically conductive sleeves 49 therein for receiving the connectors 46, thus facilitating assembly and removal of the cartridge element 37 with respect to the closure 30.

In order to facilitate connection of the wires 20 to the cartridge element, a recess 50 is formed in the base member 40 in which a plug 51 of insulating material is secured having connector 52 mounted thereon in electrical connection with the wires 20 and inserted into the sleeves 49.

It will be noted that the construction just described facilitates rapid removal and replacement of the casing and the cartridge element 37, and the charging of the casing 26.

The closure 31, as shown in Figures 2 and 3, is generally in the form of a screw ring 54 at the lower portion thereof for receiving and attaching the outlet end portion of the casing 26, and has an inwardly extending flange 55 cooperating with the outlet end of the casing to secure the disc therebetween.

If desired, discharge directing means may be associated with the closure and, as shown, may be integrally combined therewith. This may be accomplished by positioning, in spaced relation above the outlet opening 29, an inverted cone-shaped member 56 which is split diametrically by a slot 57 and has a central bore 59. The halves of this member are connected to the screw ring 54 and spaced therefrom by posts or legs 60. The effect of this construction is to permit axial flow of a portion of the charge from the casing to the vicinity of the fire while at the same time causing lateral and slightly forward flow of the remaining portion of the charge to provide a radial fan-shaped stream.

In Figure 4, a modified form of closure and discharge directing means is illustrated which comprises a cap 30' having a bore 61 in the end thereof, a nipple 62 having one end threaded and secured into the bore, flanged tubing 64 of any desirable length having one end secured to the other end of the nipple by a flanged nut 65, and a discharge directing tube 66 connected to the other end of the tubing 64. The nut 65 facilitates rapid connection and disconnection of these parts.

The tube 66 preferably is perforated, as indicated at 67, to facilitate lateral discharge and distribution of the charge of fire extinguishing agent and may be open at its end opposite the end connected to the tubing 64. The tube 66 may be in the form of a short cylinder, as shown in Figure 4, or may be in the form of a ring 69, as shown in Figure 5, for protecting the forward zone 11 of the nacelle.

The cap 30' has an internal shoulder 70 on which is mounted a baffle member 71. A spacer ring or collar 72 retains the baffle member on its seat and engages the rupturable disc to secure it to the outlet end of the casing 26 while spacing the disc and baffle member. Upon rupture of the disc, the baffle member prevents large fragments of the disc from passing into the tubing 64 and clogging the same, by causing such large fragments to be torn into smaller fragments adapted to pass through the baffle openings and subsequently through the tubing without danger of obstructing the same.

Referring now to Figure 5, there is shown a

nacelle 10 having a fire wall 15 and zones 11, 12 and 14, which are protected against fire by a modified system which differs essentially from the system shown in and described in connection with Figure 1 in that cartridges 16' are discharged by a source of fluid pressure medium and connecting tubing serving as the pressure providing means.

The system shown in Figure 5 comprises a perforated ring 69 in the forward zone 11 serving as 10 a discharge directing means and hereinafter referred to as such, one or more discharge directing means 66 of the type described in connection with Figure 4 (only one being shown for simplicity), a cartridge 16' for each of the zones having its outlet end connected in fluid flow communication with the discharge directing means in the zone, and a fluid pressure medium conducting system including conduits 74, each connected to the inlet end of one of the cartridges.

The fluid pressure medium conducting system may further comprise a receptacle 75 for storing fluid medium under pressure, such as carbon dioxide, nitrogen or the like, a manifold 76 at a central control panel connected to the outlet of the receptacle and having each of the conduits 74 connected thereto, and a valve 77 for controlling the flow of medium from the outlet of the receptacle.

The system, as shown herein, is constructed and arranged for individual operation of the cartridges. This is accomplished by providing a valve 79 in each of the conduits 74 at the control panel for individually and selectively supplying pressure medium from the manifold 76 to the cartridge or cartridges to be discharged. The valve 77 of the receptacle may be constructed and arranged for remote operation by a pull cable 82 having a handle 84 thereon located on the control panel.

While the cartridges 16' may be mounted in the zone to be protected, as shown herein, it will be understood that they may be coupled in the conduits 74 at any point thereof between the discharge directing means and the common connecting pipe 80. In some instances, it may be desirable to have access thereto for inspection and replacement without the necessity of entering the nacelle. For example, if the cartridges are at some convenient central location, as in the fuselage of the airplane, they may be inspected or replaced while the airplane is in flight.

Since the cartridges are relatively small in size and of a minimum weight, a number of spares for replacement can be carried conveniently or a quantity of fire extinguishing agent for recharging the cartridges or a supply of prefabricated charge containing refill packages may be kept on hand.

In Figure 6, a cartridge 16' is illustrated as being removably secured to the craft by a U-shaped clip or strap 85, although it will be understood that any suitable supporting or mounting means which facilitate removal and replacement may be employed.

Only the inlet end of the cartridge 16' is shown, because the outlet end may be in accordance with the outlet end of the cartridges illustrated in either Figure 2 or Figure 4. The inlet end of the casing is provided with a closure associated with pressure providing means. Such closure may be a cap 30' screw threaded to the inlet end portion of the casing which has a bore 61 in the end thereof and an internal shoulder 70 cooperating with the inlet end of the casing to secure a 75

rupturable disc 32 therebetween. A nipple 62 has one end thereof secured in the bore, and a conduit 74 formed with a flange 86 is secured to the other end of the nipple by means of a flanged nut 65, which facilitates rapid connection and disconnection for replacement and removal of the cartridge.

In operation, upon actuation of the pressure providing means of either the ignitable powder or fluid pressure medium type, pressure is established at the inlet end of the cartridge casing, which effects rupture of the disc 32 or displacement of any other seal at the inlet end and subjects charge to a pressure which is effective to cause the charge to rupture the disc or displace the other seal at the outlet end of the cartridge casing, whereby the charge is expelled and conducted to the discharge directing means.

It will, therefore, be seen that the present invention provides simple, practical, lightweight fire extinguishing systems particularly adapted for airplanes or the like and other installations where weight and space are an important factor. As will be appreciated from the foregoing description, the fire extinguishing systems are readily installed, can be adapted for operation in a great variety of sequences and combinations under the influence of manual, automatic or semi-automatic controls, and can be readily recharged even while the craft is in motion. The latter feature greatly increases the fire protection which the systems afford because the systems can be operated more than once to extinguish several fires or a series of fires while the craft is away from its base.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. Fire extinguishing means for a compartment comprising discharge means arranged for directing a fire extinguishing agent into the compartment; a source of pressure medium; a cartridge including a tubular casing for storing a charge of fire extinguishing agent having an opening at each end thereof, displaceable means for said openings for normally confining the charge in said casing, and apertured closure means secured to said casing for retaining said charge confining means; conduit means for establishing fluid flow communication between said source and one of said closure means; conduit means for establishing fluid flow communication between said other closure means and said discharge means; and coupling means for respectively connecting said conduit means and said closure means constructed and arranged to facilitate removal and replacement of said cartridge between said conduit means.

2. Fire extinguishing means for a compartment comprising discharge means arranged for directing a fire extinguishing agent into the compartment; a source of pressure medium; a cartridge including a tubular casing for storing a charge of fire extinguishing agent having an opening at each end thereof, a rupturable disc for each of said openings for normally confining the charge in said casing, and an apertured closure cap removably secured to each end of said casing for retaining said discs; a conduit for establishing fluid flow communication between

said source and one of said caps; a second conduit for establishing fluid flow communication between said other closure means and said discharge means; and coupling means for respectively connecting said conduits with the apertures of said caps constructed and arranged to facilitate removal and replacement of said cartridge between said conduits.

3. Fire extinguishing means according to claim 2, wherein baffle means are positioned between one of said discs and the aperture of said cap connected with said discharge means.

DELBERT G. FAUST.
